(57) **CLAIM**

The ornamental design for a smart watch, as shown and described.

DESCRIPTION

FIG. 1 is a front, right perspective view of the smart watch; FIG. 2 is a rear, left perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a partially enlarged view of encircled portion 9 in FIG. 1;

FIG. 10 is a partially enlarged view of encircled portion 10 in FIG. 2;

FIG. 11 is a partially enlarged view of encircled portion 11 in FIG. 4; and,

FIG. 12 is a partially enlarged view of encircled portion 12 in FIG. 6.

The broken lines shown on the drawings depict portions of the smart watch that form no part of the claimed design. The other dashed lines encircling portions of the smart watch in FIGS. 1, 2, 4, 6, and 9-12 are included to show a partially enlarged view only and form no part of the claimed design.

1 Claim, 12 Drawing Sheets
